UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

SHAFT BEARING.

1,418,366.

Specification of Letters Patent. Patented June 6, 1922.

Application filed August 9, 1920. Serial No. 402,254.

To all whom it may concern:

Be it known that I, CHARLES W. DAKE, a citizen of the United States, residing at Chicago, in the county of Cook and State 5 of Illinois, have invented a certain new and useful Improvement in Shaft Bearings, of which the following is a specification.

My invention relates to a bearing and means for mounting it, and particularly to 10 such a bearing as is intended to be used in connection with the shaft of a turbo generator and to be arranged so that it can be thoroughly lubricated. The parts are illustrated in the accompanying drawing where- 15 in Figure 1 is an axial section through the bearing and lubricating chamber; Figure 2 is a section taken on lines 2—2 of Figure 1. A is the main body of the shaft, B a hollow portion thereof, and C C' are two 20 diaphragms in the casing D which serve to form the oil chamber E having an oil well F. These diaphragms are apertured respectively at C² and C³, and in the dia- 25 phragm C is a pocket C⁴ into which is relatively loosely set the ring G. Within the ring is the bearing G' in which is rotatably mounted the hollow portion B of the shaft. J is an oil distributor device not forming a 30 part of this invention. On each side of the bearing within the ring are the spaces KK through which oil may pass on its way to or from the bearing. The right hand space K opens into the oil chamber E and the left hand space K opens into the passageway 35 L formed in the hub-like part of the dia- phragm C in connection with the pocket C⁴. A passage L' leads thence to the oil chamber and oil well. M are the governor weights and N the governor rod, but these 40 devices form no part of the present invention. The ring G preferably extends into the oil chamber E and on the walls of the oil chamber is a channel O formed by the ribs PP. This directs the oil down the 45 side of the diaphragm into the space between the ring and the hub on the dia- phragm and also when it overflows from the ring into the bearing.

The particular form, size and proportions 50 of the several parts can of course be greatly varied without departing from the spirit of my invention.

The use and operation of my invention are as follows:

55 With the device so arranged, when the

shaft rotates the oil will be distributed throughout the oil chamber and will find its way down along the walls thereof into the spaces between the ring G and the surrounding wall of the hub on the diaphragm. 60 The film of oil thus finding its way into this ring will form an oil cushion against any such lateral motion as might tend to occur due to the centrifugal action of the rotat- 65 ing parts.

The oil also finds its way into the bearing and through its several parts. All such oil is carried or travels laterally along the length of the shaft into the chamber or pas- 70 sage L and L' and thence back into the oil well.

The tendency of the oil to find its way into the space between the ring and the diaphragm hub is aided by the ribs in the side of the diaphragm, which tends to di- 75 rect the oil, which is probably on the diaphragm, to such ring.

I claim:

1. A casing having an oil chamber there- 80 in with a laterally projecting pocket in the side thereof, in combination with a shaft which passes through the chamber and pocket, and a shaft bearing comprising a ring loosely fitted in the pocket and a bearing between the ring and the shaft. 85

2. A casing having an oil chamber there- 90 in with a laterally projecting pocket in the side thereof, in combination with a shaft which passes through the chamber and pocket, and a shaft bearing comprising a ring loosely fitted in the pocket and a bearing between the ring and the shaft, said ring projecting into the oil chamber.

3. A casing having an oil chamber there- 95 in with a laterally projecting pocket in the side thereof, in combination with a shaft which passes through the chamber and pocket, and a shaft bearing comprising a ring loosely fitted in the pocket and a bearing between the ring and the shaft, and a 100 passageway leading from the inside of the pocket back into the oil chamber.

4. A casing having an oil chamber there- 105 in with a laterally projecting pocket in the side thereof, in combination with a shaft which passes through the chamber and pocket, a shaft bearing comprising a ring loosely fitted in the pocket and a bearing between the ring and the shaft, said ring projecting into the oil chamber, and a 110

passageway leading from the inside of the pocket back into the oil chamber.

5. A casing having an oil chamber therein with a laterally projecting pocket in the side thereof, in combination with a shaft which passes through the chamber and pocket, and a shaft bearing comprising a ring loosely fitted in the pocket and a bearing between the ring and the shaft, and 10 directing means on the wall of the oil chamber to direct the oil toward the ring.

6. A casing having an oil chamber therein with a laterally projecting pocket in the side thereof, in combination with a shaft which 15 passes through the chamber and pocket, and a shaft bearing comprising a ring loosely fitted in the pocket and a bearing between the ring and the shaft, said ring projecting into the oil chamber, and directing means 20 on the wall of the oil chamber to direct the oil toward the ring.

7. A casing having an oil chamber therein with a laterally projecting pocket in the side thereof, in combination with a shaft which 25 passes through the chamber and pocket, and a shaft bearing comprising a ring loosely fitted in the pocket and a bearing between the ring and the shaft, said bearing exposed on one side to the oil chamber and on the other 30 to a passage which leads into the oil chamber.

8. A casing having an oil chamber therein with a laterally projecting pocket in the side thereof, in combination with a shaft which passes through the chamber and pocket, and 35 a shaft bearing comprising a ring loosely fitted in the pocket and a bearing between the ring and the shaft, and an oil distributor mounted in the oil chamber and operated by the shaft.

40 9. A casing having an oil chamber therein with a laterally projecting pocket in the side thereof, in combination with a shaft which passes through the chamber and pocket, and a shaft bearing comprising a ring loosely 45 fitted in the pocket and a bearing between the ring and the shaft, said ring projecting into the oil chamber, and an oil distributor mounted in the oil chamber and operated by the shaft.

50 10. A casing having an oil chamber therein with a laterally projecting pocket in the side thereof, in combination with a shaft which passes through the chamber and pocket, and a shaft bearing comprising a ring 55 loosely fitted in the pocket and a bearing between the ring and the shaft, and a passageway leading from the inside of the pocket back into the oil chamber, and an oil distributor mounted in the oil chamber and 60 operated by the shaft.

11. A casing having an oil chamber therein with a laterally projecting pocket in the side thereof, in combination with a shaft which passes through the chamber and 65 pocket, a shaft bearing comprising a ring

loosely fitted in the pocket and a bearing between the ring and the shaft, said ring projecting into the oil chamber, and a passageway leading from the inside of the pocket back into the oil chamber, and an oil distributor mounted in the oil chamber and 70 operated by the shaft.

12. A casing having an oil chamber therein with a laterally projecting pocket in the side thereof, in combination with a shaft 75 which passes through the chamber and pocket, and a shaft bearing comprising a ring loosely fitted in the pocket and a bearing between the ring and the shaft, directing means on the wall of the oil chamber to 80 direct the oil toward the ring, and an oil distributor mounted in the oil chamber and operated by the shaft.

13. A casing having an oil chamber therein with a laterally projecting pocket in the side thereof, in combination with a shaft 85 which passes through the chamber and pocket, and a shaft bearing comprising a ring loosely fitted in the pocket and a bearing between the ring and the shaft, said ring projecting into the oil chamber, directing means on the wall of the oil chamber to 90 direct the oil toward the ring, and an oil distributor mounted in the oil chamber and operated by the shaft.

14. A casing having an oil chamber therein with a laterally projecting pocket in the side thereof, in combination with a shaft which passes through the chamber and pocket, and a shaft bearing comprising a 100 ring loosely fitted in the pocket and a bearing between the ring and the shaft, said bearing exposed on one side to the oil chamber and on the other to a passage which leads into the oil chamber, and an oil distributor 105 mounted in the oil chamber and operated by the shaft.

15. A casing having an oil chamber therein, and a bearing pocket in combination with a shaft which passes into the pocket, 110 and a shaft bearing comprising a ring loosely fitted in the pocket and a bearing between the ring and the shaft.

16. A casing having an oil chamber therein, and a bearing pocket in combination with a shaft which passes into the pocket, and a shaft bearing comprising a ring loosely fitted in the pocket and a bearing between the ring and the shaft, said pocket open at 115 one side to the oil chamber.

17. A casing having an oil chamber therein, and a bearing pocket in combination with a shaft which passes into the pocket, and a shaft bearing comprising a ring loosely fitted in the pocket and a bearing between the ring and the shaft, said pocket connected 125 at its sides with the oil chamber.

18. A casing having an oil chamber therein, and a bearing pocket in combination with a shaft which passes into the pocket, and a 130

shaft bearing comprising a ring loosely fitted in the pocket and a bearing between the ring and the shaft, and an oil distributor adapted to pick up the oil from the well 5 and distribute it through the oil chamber.

19. A casing having an oil chamber therein, and a bearing pocket in combination with a shaft which passes into the pocket, and a shaft bearing comprising a ring 10 loosely fitted in the pocket and a bearing between the ring and the shaft, said pocket open at one side to the oil chamber, and an oil distributor adapted to pick up the oil from the well and distribute it through the 15 oil chamber.

20. A casing having an oil chamber therein, and a bearing pocket in combination with a shaft which passes into the pocket, and a shaft bearing comprising a ring 20 loosely fitted in the pocket and a bearing

between the ring and the shaft, said pocket connected at its sides with the oil chamber, and an oil distributor adapted to pick up the oil from the well and distribute it through the oil chamber. 25

21. A casing having an oil chamber therein and a bearing pocket in combination with a shaft which passes into the pocket, and a shaft bearing comprising a ring loosely fitted in the pocket, said bearing being partially supported by a lubricating fluid. 30

22. A casing having an oil chamber therein and a bearing pocket in combination with a shaft which passes into the pocket, and a shaft bearing comprising a ring loosely fitted in the pocket, said bearing being partially positioned by a lubricating fluid. 35

Signed at Chicago, county of Cook, and State of Illinois, this 29th day of July, 1920.

CHARLES W. DAKE.
